[57] ABSTRACT

The flavor of tobacco smoke is influenced by the addition of a substance of the following formula

in which R represents $-\text{CH}_2-\text{CHO}$, $-(\text{CH}_2)_2-\text{CHO}$, $-\text{CO}-\text{CHO}$, $-\text{CH}_2-\text{CO}-\text{CHO}$, $-\text{CH}_2\text{OH}$, $-(\text{CH}_2)_2\text{OH}$, $-\text{OHOH}-\text{CH}_2-\text{CH}_3$, $-\text{CO}-(\text{CH}_2)_3\text{OH}$, $-\text{CO}-\text{CHOH}-\text{CH}_3$, or $-\text{CO}-\text{COO}-\text{C}_2\text{H}_5$. The added compound comprises approximately 0.001 percent to 1.0 percent by weight of the tobacco composition.

6 Claims, No Drawings

TREATING TOBACCO

The present invention relates to methods for influencing the flavor of tobacco smoke and a principal aim of the invention is to make it possible to produce predictable flavoring results. Although the invention is more particularly concerned with natural tobaccos, it can also be applied to synthetic or artificial tobacco foil. The invention can be applied to natural tobaccos lacking in aroma or tobaccos which are neutral in flavor. Furthermore the invention may be applied to substances to be smoked which are not of a tobacco nature, for example medicinal cigarettes or to cigarette filter materials. For the sake of convenience of terminology in the present specification and claims, and because the invention is chiefly applicable to smoking materials from the tobacco plant, all smoking and filter materials are spoken of as tobacco.

In accordance with a previous proposal as made in the German Pat. specification 1,131,580 synthetic tobacco fibers were to be produced by subjecting a chosen tobacco mixture to alternating extraction treatments to remove water-soluble and alcohol-soluble aroma materials which were then mixed in the form of a dry extract with a carrier substance of cellulose or methylcellulose material. The fibers were spun so as to produce a cigarette tobacco resembling a natural cigarette tobacco mixture.

The aim of this method was exclusively the production of a synthetic tobacco which was free of woody and cellulosic tobacco constituents. There was no intention to bring about a systematic and predictable flavoring of a given natural tobacco or natural tobacco mixture.

A similar principle was followed in the method described in the British Pat. No. 989,703 in which tobacco rich in aroma was subjected to careful extraction, for instance with ice-cold water, the extract so obtained freeze-dried and applied to tobacco which was poor in aroma. This method can be used for extracting one or more components of a tobacco and adding it to another tobacco, both tobaccos later being used for producing a cigarette tobacco mixture. The method could be used for adding the flavor of a tobacco to a tobacco mixture without the necessity of adding the tobacco itself, that is to say only its extract would be added.

Further methods of making extracts from natural tobaccos are described in the British Pat. No. 298,151. In accordance with this prior proposal tobacco waste, which could otherwise not be used, was to be subjected to water extraction and the extract used for improving the flavor of tobaccos for smoking. It is, however, not possible to produce a predictable and systematic modification of the flavor of a natural tobacco with this method.

Such a predictable modification of tobacco flavor was, however, to be pursued in accordance with the method of the U.S. Pat. No. 3,174,485 which proposed that certain organic compounds should be added to avoid variations in flavor in a particular cigarette tobacco mixture. The method was not intended to produce new flavor qualities in a tobacco.

In accordance with further known methods certain pyrrol derivatives were to be added in small quantities to tobacco. In accordance with the British Pat. No. 1,017,710 2-acetyl-5-methylpyrrol was to be added while the U.S. Pat. No. 3,280,824 proposed the addition of 2-formyl-5-methylpyrrol with a cherry aroma. In accordance with the U.S. Pat. No. 3,344,637 1-methyl-2-pyrrol-carboxaldehyde was to be used. On the other hand, a cherry flavor is so removed from that of natural tobacco that it does not appeal to the majority of cigarette smokers.

One object of the present invention is to provide a method which is suitable for supplementing and strengthening the flavor of tobaccos which are poor in aroma.

A still further object of the invention is to provide a method of producing a cigarette tobacco mixture in which the effect of expensive component tobaccos is replaced by the addition of aroma producing substances without the overall aroma of the smoke of the finished mixture being impaired.

The present invention consists in a method for influencing the smoke flavor of tobacco which comprises the addition of a compound of the following general formula

5

in which R denotes $-\text{CHO}$, $-\text{CH}_2-\text{CHO}$, $-(\text{CH}_2)_2-\text{CHO}$, $-\text{CO}-\text{CH}_3$, $-\text{CO}-\text{CH}_2-\text{CH}_3$, $-\text{CO}-\text{CHO}$, $-\text{CH}_2-\text{CO}-\text{CHO}$, $-\text{CO}-\text{CO}-\text{CH}_3$, $-\text{CH}_2\text{OH}$, $-(\text{CH}_2)_2\text{OH}$, $-\text{OH}-\text{CH}_2-\text{CH}_3$, $-\text{CO}-(\text{CH}_2)_2\text{OH}$, $-\text{CO}-\text{CHOH}-\text{CH}_3$, $-\text{CO}-\text{COO}-\text{C}_2\text{H}_5$, COOCH_3 or COOC_2H_5 .

Examination of the flavor of the smoke of tobacco treated in this manner has shown that a refreshing almond characteristic is imparted though some experts consider the flavor to be more like that of liquorice.

In tests carried out on the smoke of tobacco treated in accordance with the invention it was possible to show that 2,5- or 1,2-disubstituted pyrrols produce an influence which is unnatural, especially in the case of the 2-acetyl-5-methylpyrrol proposed in the British Pat. No. 1,017,710. On the other hand, the use of 2-monosubstituted pyrrols in accordance with the invention brings about a quite general strengthening or reinforcement of the flavor of tobacco smoke. Although it is often possible to detect a qualitative and not only a quantitative difference, such a qualitative difference is not found to be what could be described as foreign to the natural tobacco aroma and the qualitative difference does not dominate the natural flavor or impair it. The difference between the prior art disubstituted pyrrols and the monosubstituted pyrrols in accordance with the invention is substantially independent of the quantity added to the tobacco. Substituted pyrrols need only be added in small quantities, for instance as low as 0.001 percent of the weight of the tobacco, to produce an influence on the flavor of the smoke. When added in quantities of this order a compound of the type to be used in accordance with the invention, or mixtures of such compounds do not have any harmful physiological effects on the smoker. The materials to be used in accordance with the method of the invention only develop their specific aroma in the tobacco smoke: In other words any aroma that they may have in the pure state before being mixed with the tobacco is different to that which they appear to have in the tobacco smoke.

Owing to their low vapor pressure the substances to be used in accordance with the method of the invention remain in a satisfactory concentration in tobacco products despite long periods of storage so that after such periods of storage no loss in aroma can be detected. However, it is to be noted that owing to the ease with which the substances are entrained by water vapor in tobacco being smoked, the substances are highly effective in influencing the aroma of the smoke.

The monosubstituted pyrrols to be used in accordance with the invention can be used singly or mixed together and can be added to a tobacco mixture as a whole or to one component before it is added to the rest of the mixture whose flavor or aroma is to be influenced. Application can for example be by dipping the tobacco in solutions of the substituted pyrrols in suitable highly volatile solvents. Application can also be carried out by spraying on such solutions. The application can be at any suitable stage in the tobacco manufacturing process, for example in the case of cigarette production. It has been found convenient to spray on an 1-5 percent W/V ethanolic solution of the substance or substances onto cut tobacco before it is passed into a cigarette making machine. The monosubstituted pyrrols to be used in the method in accordance with the invention can be synthesised comparatively easily. 2-acylated pyrrols can for example be obtained by reaction of pyrrolmag-nesium bromide with suitable esters.

(Substituted pyrrols which can be added include 2-formyl-pyrrol, pyrrol-2-carbinol, pyrrol-2-methylketone, pyrrol-2-ethylketone, pyrrol-2- γ -hydroxypropylketone, 1-(pyrrol-2)-propandione-1,2, 1-(pyrrol-2)-propanone-1-01-2, methyl pyrrol-2-carboxylate, and ethyl pyrrol-2-glyoxylate.)

2-formylpyrrol is obtained by the Vilemeyer Reaction of pyrrol with dimethylformamide and phosphorus oxychloride with a 70 percent yield (J. Org. Chem. 20, page 668 (1955)).

The reduction of 2-acylated pyrrols to the corresponding pyrrol carbinols can be carried out in an alkaline medium.

Pyrrylmagnesium bromide reacts with butyrolactone with the formation of 2-(γ -hydroxypropyl)- α -pyrrylketone.

By the reaction with chlorocarbonic acid esters pyrrol-2-carboxylic acid esters are obtained (Garr.chim. ital. 42, II, 252).

For the synthesis of 1-(pyrrol-2)-propyndione-1,2, ethyl pyruvate is reacted with ethyl orthoformate to produce the ketal and reacted with pyrrylmagnesium bromide.

The ketoketal obtained is then heated with diluted hydrochloric acid to form the dione which is selectively reduced with sodium boron hydride to form 1-(pyrrol-2)-propyndione-1-01-2. All steps in the reaction chain produce good yields.

The following examples illustrate production of substituted pyrrols to be used in accordance with the method of the invention.

EXAMPLE I

2-formylpyrrol

While stirring 85 g. of phosphorus oxychloride was slowly added to 40 g. dimethylformamide and then, during a period of 15 minutes, 125 ml. of dichloromethane were added slowly with continued stirring. Following this 33.5 g. of pyrrol were dissolved in 125 ml. of dichloromethane and the reaction mixture was heated with reflux cooling for 15 minutes. A solution of 375 g. sodium acetate in 500 ml. of water was stirred in and in the following 10 minutes the mixture was cooled to room temperature. The methylene chloride was separated from the aqueous phase, the latter extracted a few times with ether and the combined organic phases were washed until neutral with sodium hydrogen carbonate solution. The residue was dried over sodium sulfate, filtered and subjected to evaporation. It was then distilled. The yield was 69 percent.

15 Data regarding the compound is as follows:

20	$B_{p/15} = 103^\circ - 107^\circ C.$									
	$M_{p_{\text{hexane}}} = 44^\circ - 45^\circ C.$									
	Molecular weight = 95									
	$UV_{\lambda_{\text{max}}} = 286 \text{ nm}$

In order to assess the flavor brought about by the addition of the substance to a tobacco mixture, a mixture to be used for making cigarettes of normal quality and free of any artificial flavoring substance, for example essential oils or the like, was sprayed with a 2.5 percent W/V ethanolic solution of 2-formylpyrrol, stored for a week at $20^\circ C.$ and 67 percent relative humidity and then made into cigarettes. The cigarettes so produced were then tested by a panel of experts so as to make a comparison with untreated tobacco mixture as regards flavor. The quantity of solution applied to the tobacco mixture was so chosen that the cigarettes of treated tobacco contained 0.001 percent by weight (or 0.01 percent in the tobacco smoke condensate) more 2-formylpyrrol (as regards the main smoke stream) than was the case with cigarettes of the same but untreated tobacco mixture for purposes of comparison. The necessary quantity of solvent was empirically determined in preliminary tests. The smoking of the cigarettes for these 40 preliminary tests was carried out in accordance with the VdC Standards (see Beitrage zur Tabakforschung 1, page 32 (1961), 1, page 307 (1962)) in accordance with the draft DIN Standard 10.240. The panel were practically unanimous in their verdict that the cigarettes made of treated tobacco were 45 fuller in their general flavor qualities, there being a distinct almond savor.

50

EXAMPLE II

pyrrol-2-carbinol

A solution of 11 g. of sodium borohydride in 55 ml. of water was rapidly added while stirring to a solution of 10 g. 2-formylpyrrol in 170 ml. water. After stirring for a further hour potassium carbonate was added till saturation was obtained, the aqueous phase was extracted with ether, the extract dried over sodium sulfate and the ether evaporated. The residue was then 65 distilled under reduced pressure. The yield was 83 percent.

75	$B_{p/15}$	$127^\circ - 128^\circ C.$
	Molecular weight	95
	$UV_{\lambda_{\text{max}}}$	217 nm

As was the case with example I the smoke was found to be of a smooth richness with an improved general flavor level. The V-mark was more intensive than was the case with untreated cigarettes taken for comparison purposes.

EXAMPLE III

pyrrol-2-methylketone

A solution of 110 g. ethyl bromide in 100 ml. absolute ether were added slowly while stirring to 24 g. magnesium in 200 ml. absolute ether and after 30 minutes had elapsed a solution of 76 g. pyrrol in absolute ether was added. Following this the reaction solution was held for 30 minutes at the boiling point and then cooled to room temperature. After the addition of 97 g. ethyl acetate in 100 ml. absolute ether the reaction mixture was again held for 30 minutes at the boiling point and after cooling to room temperature 1 mole of 10 percent hydrochloric acid was added. The organic phase was separated from the aqueous phase, dried over sodium sulfate and the ether evaporated. The residue was distilled under reduced pressure. The yield was 73 percent.

As was the case with tobacco treated with the material of example I the smoke had a smooth V-mark with a generally more pronounced overall impression with a distinct almond oil flavor.

EXAMPLE IV

pyrrol-2-ethylketone

Using the same procedure as described in the following example V 6.7 g. pyrrol, 12 g. ethyl bromide, 2.7 g. magnesium and 11.2 g. ethyl propionate were used to produce 8.8 g. pyrrol-2-ethylketone, the yield being 72 percent.

Cigarettes produced with tobacco flavored with pyrrol-2-ethylketone produced smoke which had a clearly more pronounced flavor than was the case with cigarettes made of untreated tobacco. There was also an almond savor.

EXAMPLE V

pyrrol-2-γ-hydroxypropylketone

6

The pyrrolmagnesium bromide prepared using 6.7 g. pyrrol, 12 g. ethylbromide and 2.7 g. magnesium in accordance with example III was added while stirring to a solution of 8.6 g. butyrolactone in 50 ml. of absolute ether. After stirring intensively for a further 2 hours a molar quantity of hydrochloric acid was added and the preparation carried out as in example III. The yield of pyrrol-2-γ-hydroxypropylketone amounted to 41 percent.

		N	8.39
			8.42

Testing as carried out in accordance with example I showed that there was a pronounced heightening of the flavor level with a mild almond savor.

15 The amount of substance added to the tobacco in accordance with the invention can be within the range of 0.001 to 1.0 percent by weight of the tobacco, the preferred range being 0.01 to 0.1. More than one of the substances can be 20 added and in this case the ranges applied to the combined weight of the substances.

The method of the invention can be so carried out as to lead to the replacement of one or more components in a tobacco mixture containing the same tobacco smoke flavoring components.

25 What we claim is:

1. A method of improving the flavor of tobacco smoke which comprises adding to the tobacco a small amount of a flavorant, said flavorant consisting essentially of a compound of the following general formula

30

35

in which R denotes $-\text{CH}_2-\text{CHO}$, $-(\text{CH}_2)_2-\text{CHO}$, $-\text{CO}-\text{CHO}$, $-\text{CH}_2\text{CO}-\text{CHO}$, $-\text{CH}_2\text{OH}$, $-(\text{CH}_2)_2\text{OH}$, $-\text{OHOH}-\text{CH}_2-\text{CH}_3$, $-\text{CO}-(\text{CH}_2)_3\text{OH}$, $-\text{CO}-\text{CHOH}-\text{CH}_3$, $-\text{CO}-\text{COO}-\text{C}_2\text{H}_5$, said compound comprising approximately 0.001 percent to 1.0 percent of the weight of the tobacco composition and being without any harmful physiological effect on the smoker of the tobacco composition.

40 2. A method in accordance with claim 1 in which pyrrol-2-carbinol is used.

3. A method in accordance with claim 1 in which pyrrol-2-hydroxypropylketone is used.

4. A method in accordance with claim 1 in which 1-(pyrrol-2-propanone-1-ol-2 is used.

5. A method in accordance with claim 1 in which ethyl pyrrol-2-glyoxylate is used.

6. A method in accordance with claim 1 in which the compound is added in a total quantity equal to 0.01 to 0.1 percent of the weight of the tobacco.
